UNITED STATES PATENT OFFICE

CHARLES W. CRANNELL, OF BIG SPRINGS, NEBRASKA, ASSIGNOR OF ONE-THIRD TO ANNA C. BARNES, OF BIG SPRINGS, NEBRASKA, AND ONE-THIRD TO ADA A. WOLF, OF CHAPPELL, NEBRASKA

RACK FOR TRUCKS OR WAGONS

Application filed July 24, 1928. Serial No. 294,963.

My invention relates to improvements in racks for trucks or wagons.

The object of my invention is to provide an improved beet rack adapted to be carried by a truck or wagon, whereby the beets or other articles carried in the rack can be readily dumped therefrom, and at the same time providing means whereby the swinging side is automatically returned to its closed position and automatically locked.

Another object of my invention is to provide a rack of this character in which the swinging side is held in its closed position by two chains and provided with means for simultaneously releasing both of the chains, whereby the swinging side is adapted to swing down by the weight or pressure of the beets or other articles in the rack, and are allowed to pass from the rack.

20 A further object of my invention is to provide a rack of this character which is very durable, simple in construction and provided with certain details of structure and combination of parts hereinafter more fully set forth.

In the accompanying drawings:—

Figure 1 is a side elevation of my improved rack showing the swinging side locked in its upward position.

30 Figure 2 is a similar view showing the chains released so that the weight of the beets or the other articles in the rack will cause the side to swing downwardly.

Figure 3 is a transverse sectional view taken on the line 3—3 of Figure 1.

Figure 4 is a side elevation showing the side swung downwardly.

Applicant is aware that racks of this character are old in the art, in which the swinging side is held in its upward or closed position by means of two chains adapted to interlock with slots, such as shown in Patent No. 1,815,386. In such a structure as shown in this patent, it requires two persons to release the swinging side, or else a single person has to walk to one end to release one chain and then to the other end to release the other chain. In such structures, the chains are released by striking the same with a bar to disengage the links of the chain from the slot

and there is no assurance that the chains will pass freely through the eyes and allow the swinging side to swing all the way down as the chains are often caught in the slots and the swinging side stopped at an intermediate point.

In my improved rack the two chains are simultaneously forced out of the slots by a single movement of the levers, and the slots closed by said means so that the chains passing freely through the eyes can not pass into the slots to stop the swinging movement of the side at an intermediate point.

Referring now to the drawings, 1 represents my improved rack, which is of a shape and size to fit the chassis of a truck or the running gear of a wagon, and while I have shown this rack specially designed for handling beets, it will be understood that the same could be used in handling grain or many other farm products, and the same idea could be used in other places where a swinging door or gate is used.

The rack 1, as shown, has the side 2 hinged to the bottom 3 by means of hinges 4 and 5. These hinges, as shown, are of strap form, and the straps 6 forming one portion of the hinge extending a considerable distance across the bottom of the rack, and the straps 7 secured to the side 2 extending entirely across the side and above the upper edge thereof, as will be hereinafter more fully described. In order that the side 2 will automatically return to its vertical or closed position after the weight or pressure of the contents thereof is taken off, I provide a coil spring 8 which has its two ends 9 and 10 extending therefrom mid-way between the diameter of the coil. The end 10 is rigidly fastened to the bottom 3 of the rack and the other half extending beyond the side 2 of the rack. The end 9 normally holds the side 2 in the position shown in Figure 1 of the drawings, when there is no pressure thereon. Secured to the ends 11 of the rack are the hooks 12 to which the chains 13 and 14 are connected and by this arrangement it will be seen that the chains are readily detached from the body of the rack.

The straps 7 of the hinges, as heretofore

stated, extend upwardly above the upper edge of the side 2 of the rack and are provided with the enlarged portion 15, which extends slightly to one side. The enlarged portions 5 above the edge of the side 2 are provided with circular openings 16 having communicating with their lower ends the obliquely arranged slots 17.

Pivoted upon the straps 7, at 18 and 19, 10 are the two levers 20 and 21, which have their lower ends offset as indicated at 22, whereby the same may be gripped by hand for operating the same. A link 23 has its ends pivotally connected at 24 and 25 to the levers 20 15 and 21 below the pivots 18 and 19, whereby the said levers are connected to operate together and by moving either lever the other is operated. The upper ends of the levers 20 and 21 are provided with enlarged heads 26 20 and 27 having flat edges 28 and 29, which are in a horizontal plane with the lower edge of the slots 17 when the levers are in the position shown in Figure 1 of the drawings. Extending from the said flat edges 28 and 29 are 25 two circular edges 30 and 31 which are in the same arc of a circle as that of the opening 16 in the enlarged portions 15 of the strap 7. The chains 13 and 14 pass through the opening 16 and are provided at the ends with 30 weights 32 and 33, whereby the chains are drawn downwardly into the slots 17, and the links thereof are prevented from sliding in the slots, and the side 2 of the rack is held in the position shown in Figure 1 of the drawings. 35

When it is desired to dump the rack an operator standing at either end, either pushes or pulls one of the levers 20 and 21, which causes the flat edges 28 and 29 to engage the 40 links of the chain 13 and 14 and gradually force them upwardly out of the slots 17, and the continued movement of the lever causing the slots to be closed with the curved edges 30 and 31 covering the slots, whereby circular 45 openings are maintained to allow the free passage of the chains therethrough.

The upper ends of the levers 20 and 21 are provided with lugs 34 and 35, which engage the enlarged portion 15 of the straps 7, and 50 limit the movement of the levers so as to assure the position shown in Figure 2 of the drawings. The moment the chains are forced out of the slots 17 the pressure of the contents of the rack will force the side 2 downwardly 55 and the chains will freely pass through the circular openings 16. After the rack has been dumped the spring 8 normally returns it to the closed position and the levers 20 and 21 are returned to the normal position shown in 60 Figure 1 of the drawings, and the links of the chains 13 and 14 will find their way into the slots 17 and the side is again locked against downward movement.

Having thus fully described my invention 65 what I claim is:—

1. A rack of the character described comprising a body portion, a hinged side, chains secured to the body portion and passing through guide-ways carried by the hinged side and interlocked with said guide-ways, and means for simultaneously disengaging the chains with the guide-ways to allow the side to swing downwardly. 70

2. A rack of the character described comprising a body portion, a hinged side carried thereby, chains secured to the body portion and passing through guide-ways carried by the hinged side and adapted to interlock with slots communicating with said guide-ways, and means for simultaneously moving the chain out of the slots to allow the chains to 80 freely pass through the guide-way allowing the side to swing downwardly. 75

3. A rack of the character described comprising a body portion, a side hinged to the body portion, chains secured to the body portion adjacent the ends and passing through guide-ways carried by the side and adapted to enter slots communicating with the guide-ways, and means for simultaneously forcing the chains out of the slots and closing the same to allow the chains to freely pass 90 through the guide-ways and allow the side to swing downwardly. 85

4. A rack of the character described comprising a body portion, a hinged side, chains secured to the body portion and passing through guide-ways carried by the upper end of the side and adapted to enter obliquely arranged slots communicating with the guide-ways, and means for simultaneously forcing the chains out of the slots and closing the slots to form smooth guide-ways whereby the side may swing downwardly. 95

5. A rack of the character described comprising a body portion, a hinged side, chains secured to the body portion and passing through guide-ways carried by the upper end of the side and adapted to enter obliquely arranged slots communicating with the guide-ways, two pivoted levers connected by a link 105 adapted to simultaneously move the chains out of the slots and close the same whereby the side may swing downwardly, and the chains travel freely through the guide-ways. 110

6. A chain locking member comprising a body portion having a circular opening therein having an obliquely arranged slot communicating with the lower end, a pivoted lever adjacent said slot and having a straight face adapted to force the chain out of said slot and having a curved face adapted to close the slot to form a continuation of the circular opening. 115

7. A rack of the character described comprising a body portion, a side hinged thereto and normally held in a vertical position by a spring, chains secured to the body portion and passing through guide-ways carried by the upper end of the side and adapted to inter- 120 125

lock with slots communicating with the guide-ways, and means for simultaneously moving the chains upwardly out of the slots to allow the same to freely run through the guide-ways upon the upward movement of the side.

5 8. A rack of the character described comprising a body portion, a side hinged thereto, chains secured to the body portion and passing through guide-ways carried by the upper 10 end of the side and adapted to interlock with said guide-ways, and means for simultaneously moving said chains out of their interlocked position with the guide-ways.

9. A rack of the character described comprising a body portion, a hinged side carried by the body portion having strap hinges, the straps of the hinges extending upwardly beyond the upper end of the side and having eyes formed therein, said straps having 20 obliquely arranged slots communicating with the lower ends of the eyes, pivoted levers carried by the straps, a link pivotally connecting the levers, said levers having straight faces adapted to engage the chains and force them 25 out of the obliquely arranged slots and having curved faces adapted to close the said slots to form circular eyes.

10. A rack of the character described comprising a body portion, a side hinged to the 30 body portion at its lower end, eyes carried by the upper end of the hinged side, chains secured to the body portion, passing through the eyes, having their lower ends weighted and interlocking with the eyes, and means for 35 simultaneously moving the chains out of their interlocked relation with the eyes.

11. A rack of the character described comprising a body portion, a side hinged to the body portion at its lower edges, a chain secured at each end of the body portion and passing through eyes carried by the side adjacent its ends, said eyes having obliquely arranged slots communicating therewith and into which the links of the chains are adapted 45 to pass, and pivoted levers operatively connected together and adapted to simultaneously move the chains upwardly out of the slots to allow the chains to freely pass through the eyes.

50 12. A rack of the character described comprising a body portion, a hinged side carried by the bottom of the body portion, an eye carried by the upper edge of the side adjacent each end, and having a slot communicating 55 with the eye, chains secured to the body and passing through said eyes and adapted to enter said slots, levers pivoted adjacent said eyes and operatively connected together and having flat faces adapted to engage the chains 60 and lift them out of the slots, and curved faces adapted to close the slots and form continuations of the eyes.

In testimony whereof, I have signed this specification.

65 CHARLES W. CRANNELL.
